United States Patent Office

Des. 229,634
Patented Dec. 18, 1973

229,634

ELECTRONIC DATA PRINTER

Harold William Bermender, Jr., 38 Ridge Road,
Hamden, Conn. 06517

Filed July 1, 1971, Ser. No. 159,091

Term of patent 7 years

Int. Cl. D18—02

U.S. Cl. D64—11 R

FIG. 1

FIG. 4

FIG. 3

FIG. 2

FIG. 1 is a three-quarter perspective view of an electronic data printer showing my new design;

FIG. 2 is an elevational view of the opposite side thereof;

FIG. 3 is a rear elevational view thereof; and

FIG. 4 is a bottom plan thereof.

I claim:

The ornamental design for an electronic data printer, as shown.
